(57) **CLAIM**

The ornamental design for a flexible bracelet, as shown and described.

DESCRIPTION

FIG. 1 is a perspective view of a flexible bracelet showing my new design;

FIG. 2 is a top plan view thereof, the bottom plan view being a mirror image thereof;

FIG. 3 is a front elevational view thereof, the rear elevational, left side elevational and right side elevational views being mirror images thereof;

FIG. 4 is a perspective view of a second embodiment of a flexible bracelet showing my new design;

FIG. 5 is a top plan view thereof, the bottom plan view being a mirror image thereof; and,

FIG. 6 is a front elevational view thereof, the rear elevational, left side elevational and right side elevational views being mirror images thereof.

The broken lines on the drawings represent removable medallions, held in place by the shown pins and holes, and form no part of the claimed design.
